(57) **CLAIM**

The ornamental design for a television receiver, as shown and described.

DESCRIPTION

1. Television receiver

1.1 : Perspective

1.2 : Front

1.3 : Back

1.4 : Left

1.5 : Top

1.6 : Bottom

1.7 : Back perspective view

1.8 : Enlarged view 1

1.9 : Enlarged view 2

1.10 : Enlarged exploded view

The fine lines on the drawings indicate the display part or transparent materials; the broken lines depict portions of the television receiver that form no part of the claimed design; reproduction 1.1 is a front perspective view of the television receiver; reproduction 1.2 is a front view thereof; reproduction 1.3 is a back view thereof; reproduction 1.4 is a left view thereof where the right view is a mirror image; reproduction 1.5 is a top view thereof; reproduction 1.6 is a bottom view thereof; reproduction 1.7 is a back perspective view thereof; reproductions 1.8 and 1.9 are partial enlarged views of the center of front and back part of the claimed design; and reproduction 1.10 is an enlarged exploded view showing an example of a state where the transparent logo part is separated.

1 Claim, 10 Drawing Sheets
